CLAIM

The ornamental design for a combined exercise glove and flask, as shown and described.

DESCRIPTION

FIG. 1 is a front perspective view of a combined exercise glove and flask;

FIG. 2 is a rear perspective view thereof;

FIG. 3 is a rear elevational view thereof;

FIG. 4 is a front elevational view thereof;

FIG. 5 is a right side elevational view thereof;

FIG. 6 is a left side elevational view thereof;

FIG. 7 is a top plan view thereof;

FIG. 8 is a bottom plan view thereof;

FIG. 9 is an exploded front perspective view thereof; and,

FIG. 10 is an exploded rear perspective view thereof.

The broken lines showing grip pads are included for the purpose of illustrating environmental structure and form no part of the claimed design.

1 Claim, 10 Drawing Sheets(56)
